UNITED STATES PATENT OFFICE.

ROY A. WASHBURN, OF MASON CITY, IOWA.

CIRCUIT-CLOSER.

1,199,843.

Specification of Letters Patent.

Patented Oct. 3, 1916.

Application filed November 22, 1915. Serial No. 62,775.

To all whom it may concern:

Be it known that I, Roy A. Washburn, a citizen of the United States, residing at Mason City, in the county of Cerro Gordo and State of Iowa, have invented certain new and useful Improvements in Circuit-Closers; and I do declare the following to be a full, clear, and exact description of the invention, such as will enable others skilled in the art to which it appertains to make and use the same.

My invention is an improved circuit closer for the electrical signaling systems of automobiles and other types of vehicles, and has for its object to provide a simple arrangement of parts whereby both visual and audible warnings may be given when stopping the machine or when turning to the right or left, provision being also made whereby the audible signal may be used independently of the visual signals.

With this general object in view, the invention consists of certain novel features of construction and of unique combinations of parts to be hereinafter fully described and claimed, the descriptive matter being supplemented by the accompanying drawings which constitute a part of this application and in which:

Fig. 1 is a perspective view of an automobile equipped with a signaling system operated by the improved circuit closer; Fig. 2 is a rear elevation of the signal light casing of the automobile; Fig. 3 is a longitudinal section thereof taken on the plane indicated by the line 3—3 of Fig. 2; Fig. 4 is a top plan view of the switch; Fig. 5 is a longitudinal sectional view thereof as seen on the plane of the line 5—5 of Fig. 4, and Fig. 6 is a diagram of the system with the improved circuit closer applied.

In specifically describing the invention shown in the drawings above briefly described, similar reference characters will be placed on corresponding parts throughout the several views of such drawings, and reference will be herein made to the numerous elements by their respective indices. To this end, the numeral 1 refers to an automobile of common construction having mounted on its rear end an appropriate casing 2 with a slot 3 in its side, while its rear end is equipped with a number of translucent lenses or the like 4 of appropriate colors, an additional and preferably red lens 5 being also carried by the rear end of the

casing. The three lenses 4 are formed with the letters "S," "L," and "R," such letters being either totally or partially transparent as desired, and representing respectively the words "Stop" or "Slow," "Left," and "Right." Thus it will be seen that if proper lamps are illuminated within the casing 2, the rays thereof will illuminate the lenses 4 to give warning when the driver of the machine will stop, or when he will turn to the right or left.

The lights above mentioned are represented in the drawings by the numerals 6, being preferably housed in appropriate reflectors 7 carried within the casing 2, while an additional lamp 8 is positioned contiguous to the red lens 5 and is adapted to be constantly illuminated to serve as the tail light of the machine. Since the slot 3 in the casing is so disposed with respect to the lamp 8 as to allow rays from the latter to be projected through the former, the license number 9 of the machine may be illuminated from said lamp.

The dash of the automobile 1 is equipped with an electric lamp 10 adapted to be illuminated when any one of the lamps 6 is operated, thus allowing the operator of the machine to readily ascertain whether or not the circuits of said lamps are completed, and in addition to said lamp 10, an audible electric signal 11 is mounted adjacent said dash or at another appropriate point. The signal 11 is represented in the present embodiment 90 of the invention in the form of an electric horn, but obviously if might well be a bell if the system is to be applied to electric automobiles.

The current for operating the numerous lights and the signal 11 is taken from an appropriate battery 12 carried at any preferred point on the machine and is properly directed through wiring yet to be described by a switch 13 which is mounted on the 100 steering wheel of the machine or at another point readily accessible to the driver.

The switch 13 is carried within an appropriate casing 14 of insulating or other suitable material and consists of an imperforate bottom contact plate 15, an intermediate contact plate 16 slit transversely at intervals and thus divided into a plurality of contact fingers 17, and a trio of additional fingers 18 disposed above three of the fingers 110 17. The remaining finger 17 is equipped with an operating knob 19, while the fingers

18 are provided with similar knobs 20, all of the knobs being passed through openings in the top of the casing 14. By any preferred means such as that designated at 21 5 in the drawings, the plates 15 and 16 are insulated from each other in spaced relation, and by the insulation 22, the fingers 18 are in turn insulated from the plate 16, all of this being essential for reasons to become 10 obvious as the description proceeds.

The lower contact plate 15 is electrically connected with one terminal of the battery 12 by a wire or the like 23, one terminal of the audible signal 11 is connected by a wire 15 24 with the plate 16, and other wires 25 lead from the individual fingers 18 to one terminal of the three lamps 6. The other terminals of these lamps are connected by a wire 26 with one terminal of the lamp 10, while 20 leading from the other terminal of the latter to the remaining terminal of the battery 12, is a wire 27. The last named terminal of the battery is connected electrically with the remaining terminal of the signal 11 by a 25 wire 28.

In addition to the wiring above described, wires 29 and 30 lead from the opposite terminals of the battery 12 to such terminals of the tail light 8, a switch 31 being located 30 in one of said wires, whereby the tail light may be thrown out of use during the day.

With all parts of the device constructed and connected as above described, by pressing upon the knob 19, the operator will 35 bring one finger 17 in contact with the plate 15, whereupon the current will travel from the battery through the wire 23 and plate 15, and through the finger 17 and wire 24 to the audible signal 11, from which it will 40 return to the battery through the wire 28, thereby sounding said signal. It is to be observed that this takes place without illuminating any of the lights 6. If, however, the operator intends turning, say to the 45 left, he will press one of the buttons 20, such button being provided with any preferred type of indicating means not shown. The result of this is that one of the fingers 18 contacts with the finger 17 beneath it and 50 forces the latter against the plate 15. The current within the latter, fed thereto by the wire 23, will now flow through the active finger 17 and plate 16 and will pass from the latter through the signal 11 as above described, thus sounding the same. Simultaneously with this operation, the current will pass from the plate 15 through the active fingers 17 and 18, and from the latter through its wire 25 to the left hand light 6, 55 from which light it will return to the battery through the wires 26 and 27, and light 10. Thus, if the lamp 6 operates, the lamp 10 will also be illuminated, but if the fila-

ment in said light 6 should be broken, or if said lamp should have jarred loose from its 65 socket, it is obvious that the lamp 10 will not operate. Thus, the operator may readily ascertain at all times whether or not the warning lights are operating.

From the foregoing description, taken in 70 connection with the accompanying drawings, it will be obvious that the object of the invention has been attained; and that further description or exposition is therefore unnecessary.

75

In the drawings, certain specific arrangement of parts have been shown for the attainment of probably the best results, and in the preceding such arrangements have been described, but obviously, numerous 80 minor changes may be resorted to within the spirit of the invention as claimed.

I claim:

1. A circuit closer of the class described comprising a base plate of conducting material, a plurality of resilient contact fingers spaced from one face of said plate and having operating buttons for forcing them toward said plate, said fingers being insulated from each other and from the base plate, 85 and a resilient plate interposed between said fingers and the base plate and spaced therefrom, said resilient plate being insulated from said base plate and fingers and being slotted inwardly from one edge to form an additional plurality of resilient contact fingers to be forced against the base plate by movement of the first named fingers.

2. A circuit closer of the class described comprising a base plate of conducting material, a plurality of resilient contact fingers spaced from one face of said plate and having operating buttons for forcing them toward said plate, said fingers being insulated from each other and from the base plate, and a resilient plate interposed between said fingers and the base plate and spaced therefrom, said resilient plate being insulated from said base plate and fingers and being slotted inwardly from one edge to form an additional series of resilient contact fingers, certain of which are adapted to be forced against the base plate by movement of the first named fingers, one of the fingers of said additional series being independent of said first named fingers and having an individual operating button for forcing it against the base plate.

In testimony whereof I have hereunto set my hand in presence of two subscribing witnesses.

ROY A. WASHBURN.
